RANGE SPLASH BACK

Ralph E. Kruck, Clinton, Conn., assignor to Majestic Manufacturing Company, St. Louis, Mo., a corporation of Missouri

Application October 24, 1949, Serial No. 5,681

Term of patent 14 years

(Cl. D81—25)

To all whom it may concern:

Be it known that the undersigned, Ralph E. Kruck, a citizen of the United States, residing in Clinton, Connecticut, has invented a new, original, and ornamental Design for a Range Splash Back, of which the following is a specification, reference being had to the accompanying drawing, forming a part thereof, in which:

Fig. 1 is a front elevational view of a range splash back embodying my new design;

Fig. 2 is a top plan view of the splash back;

Fig. 3 is a side elevational view of the splash back, taken from the right side of Fig. 1; and

Fig. 4 is an enlarged transverse vertical sectional view taken on the line 4—4 in Fig. 1, the bulb being shown in dotted lines.

I claim:

The ornamental design for a range splash back, substantially as shown.

RALPH E. KRUCK.
